UNITED STATES PATENT OFFICE.

GRENVILLE MELLEN, OF WEST ORANGE, NEW JERSEY, ASSIGNOR TO CONTINUOUS CASTING CORPORATION, OF NEWARK, NEW JERSEY, A CORPORATION OF VIRGINIA.

GUIDE FOR CONTINUOUS CASTING-MACHINES.

1,139,889.

Specification of Letters Patent. Patented May 18, 1915.

Application filed February 2, 1915. Serial No. 5,773.

To all whom it may concern:

Be it known that I, GRENVILLE MELLEN, a citizen of the United States, residing at Llewellyn Park, West Orange, in the county of Essex and State of New Jersey, have invented certain new and useful Improvements in Guides for Continuous Casting-Machines, of which the following is a specification.

- 10 My invention relates to guides for continuous casting machines, and has for its object to provide means for holding in close metal-sealing engagement, the mold-blocks used in machines such as those shown in my
15 prior applications Serial No. 748,251, filed Feb. 13, 1913 and Serial No. 839,045, filed May 16, 1914. The mold-blocks are connected together in two endless chains and when brought into coöperating engagement
20 form a continuous mold cavity, open at each end. Molten metal introduced at one end into the mold cavity is congealed therein to form a solid rod, which is discharged at the other end. In my prior machine, holding
25 down spring-pressed guides extending over a number of mold-blocks were provided, but with this arrangement when any small particle or obstruction found its way between the longitudinal horizontal joining faces of
30 the blocks, the whole guide was lifted, allowing the adjacent blocks to be separated by the pressure of the molten metal with the extrusion of molten metal into the gap, with the resultant formation of an objectionable
35 longitudinal fin on the side of the rod. My present invention obviates this difficulty.

In the drawings—Figure 1 is a section through a part of the machine; Fig. 2 is a plan of the guide; Fig. 3 is an elevation of
40 Fig. 2; Fig. 4 is a transverse section on plane 4—4 of Fig. 3; Fig. 5 is a vertical longitudinal section on plane 5—5 of Fig. 2; Fig. 6 is a section on plane 6—6 of Fig. 1 some of the parts being, for clearness sake,
45 shown in elevation; and Fig. 7 is a section showing a modification.

As shown in Fig. 1, the mold-chains are made up of a series of mold-blocks A, B, passing around sprockets 51, 52, and are brought into coöperating engagement between the fixed guide 74, and the spring-pressed guide 73.

The present invention relates more particularly to the spring-pressed guide and

comprises, as shown, a body portion C having at its lower portion a recess H, within which is mounted a sheet steel plate H' with its ends turned up and fitted into sockets I. Bearing on the plate H' are a series of springs E, set in recesses G in the body portion, and adjusted by bolts D to the required tension.

P, P are bolts screwed into the plate H', the heads of the bolts resting in sockets in the body portion (see Fig. 5), whereby the plate H', while freely movable under the pressure of springs E, is prevented from disengagement with the body portion when the guide 73 is removed or replaced, as a whole. The guide 73 is held in place by posts F, F', the post F at the entrance end preferably being adjustably but unyieldingly held, while the other post F' is preferably yieldingly mounted, the compression spring K pressing the pin F' downward. The guide 73 may therefore yield slightly at its lower end. In practice, with a steel plate three thirty-seconds of an inch thick, it is found that there is sufficient local yielding of the guiding surface in contact with any block, to localize the fin formation to that particular block, the preceding and succeeding coöperating blocks being none the less held in such complete metal-sealing engagement that no fins are formed between them.

My invention may obviously be applied to only one or to both of the guides, and both of the posts F, F' may be mounted to exert spring pressure on the backing block 90 if desired. The guide 73 is adjusted to its position by means of wedges L, L', each wedge being held in adjusted position by screws M, M', the backs of the wedges bearing against the frame of the machine. Additional side guides N, N' bear against the sides of the mold-blocks, the guide N being rigidly, but adjustably held, while the guide N' is yieldingly held against the molds by spring O, the tension of the spring being 100 adjusted by nut O'.

In Fig. 7 is shown a modification in which the plate H' is pressed against the mold-blocks by the shoe-pieces H''. These shoe-pieces have rods F', which are pressed inwardly by springs K', and are adjusted by wedge-pieces L'', in the same manner as the wedges L shown in Fig. 6.

I claim:—

1. A guide for continuous casting machines having movable mold-sections, comprising a body portion, a bottom therefor consisting of a sheet of resilient material, and a series of springs pressing against said sheet.
2. A guide for continuous casting machines having movable mold-sections, comprising a body portion, a bottom therefor consisting of a sheet of resilient material, and a series of springs pressing against said sheet, said body portion being held unyieldingly near one end and yieldingly at the other end.
3. A guide for continuous casting machines having movable mold-sections, comprising a body portion, a bottom therefor consisting of a sheet of resilient material movably secured to said body portion, and a series of springs pressing against said sheet.
4. A guide for continuous casting machines having movable mold-sections, comprising a body portion having sockets near each end thereof, a resilient metal sheet having its bent ends loosely engaging said sockets, means for preventing disengagement of said sheet from said portion comprising bolts secured to said sheet, the shanks of said bolts being free to move in said body portion, the heads of said bolts

adapted to engage the body portion, and a series of springs pressing against said sheet.

5. In a continuous casting machine having movable mold-sections, the combination with a series of molds of a guide, rigid holding means near one end thereof, resilient holding means near the other end of the guide, and means for adjusting each of said holding means.

6. In a continuous casting machine having movable mold-sections, the combination with a series of coöperating mold sections, of a rigid and an adjustably resilient guide bearing against the backs of said molds, and adjustably rigid and adjustably resilient guides bearing against opposite sides of said molds near their meeting edges.

7. In a continuous casting machine having a series of movable mold sections, a guide comprising a resilient plate bearing against said mold sections.

8. In a continuous casting machine having a series of movable mold sections, a guide comprising a resilient plate bearing against said mold sections, and a series of springs pressing against said plate.

In testimony whereof I affix my signature in presence of two witnesses.

GRENVILLE MELLEN.
